UNITED STATES PATENT OFFICE.

MAX VOGEL, OF FRANKFORT-ON-THE-MAIN, GERMANY.

NOTEBOOK.

Application filed August 20, 1926, Serial No. 130,488, and in Germany November 11, 1925.

This invention relates to book covers of the type in which the leaves are removably held within the cover by a C-shaped clamping spring embracing the back of the cover, 5 the clamping spring being slid on in a longitudinal direction and taken off in the same way.

In fitting clamps of this type the narrow slit edges of the clamp are liable to damage 10 the back, which is of flexible material, such as leather, artificial leather, wax cloth, stiff linen or the like.

In order to avoid this disadvantage, the 15 sides of the cover of the book, in accordance with the present invention, are provided with strip-like layers or coatings, which serve as a guide for the edges of the clamp. There may be used as the coatings strips of 20 papier mâché, gummed to the sides of the cover, but preferably these coatings consist of metal strips which are much more durable. Such strips may also be secured by means of adhesive.

It is preferred, however, to attach the 25 metal rails or strips closely to the covers by clamping means. For this purpose the rails are bent to hook shape at their ends and embrace the edges of the cover. Moreover, the rails may be riveted to the covers and 30 such rivets may be formed as part of the material of the rails themselves. In order that the clamp cannot be withdrawn laterally by force from the cover—a contingency which might arise due to ignorance of the 35 method of removing the cover—the rails or strips are formed with longitudinal corrugations in which the somewhat rounded longitudinal edges of the clamp are guided. These corrugations at their opposite sides, 40 under the clamping action, are pressed into the resilient cover and into the sheets held between the covers. The great advantage of this arrangement is that the sheets are better gripped, while the cover, and in consequence the book, may be opened out completely.

The clamp must be highly resilient in order that it will retain its properties after 50 long use. To overcome the tendency of the clamp to close, a considerable force is required, and the natural smoothness of the clamp renders its slidale removal for opening more difficult. A further characteristic of the invention, therefore, consists in 55 this that the clamp is roughened, for example, it is formed with a ribbed surface, par-

ticularly at the point where it is gripped by the fingers.

An embodiment of the invention is illustrated in the accompanying drawings, in 60 which

Fig. 1 is a perspective view showing a clamp not completely in position,

Fig. 2 is a plan view, and

Fig. 3 shows the cover in open position 65 and empty.

Referring to the drawing, the cover of the book *b* consists as usual of flexible sides *a*¹, *a*², and a back *d* formed in one therewith, or subsequently attached thereto. To the 70 cover are fitted corrugated metal rails *e*¹, *e*², secured by means of hollow rivets *g* formed in the material of the rails and driven into the cover. In lieu of rivets or in addition thereto, the rails may be overturned at their 75 projecting ends, so as to grip the edges of the cover as shown at *i* (see particularly Fig. 3).

The rails serve as guides for the usual clamp *k*. In order at least to render difficult the removal of the clamp in a transverse direction, the rails are formed with longitudinal grooves *m*, in which the rounded edges *k*¹ of the clamp *k* engage. Under the action of the clamp the corruga- 80 tions *m* press into the sheets *b* and form edges about which the sheets may bend when the book is opened, so that the back can be 85 opened fully, which is very desirable for inspection and for writing therein.

In order to permit of gripping the clamp in moving it into and out of position such clamp is roughened, e. g., is ribbed, at least where it is to be gripped by the fingers as 90 indicated by *n*, Fig. 1.

I claim:—

1. A note book comprising in combination with a cover, a C-shaped clamping spring 100 slideable longitudinally of and embracing the cover and adapted to hold the leaves within the book and longitudinally-extending guide rails on said cover for guiding said clamping spring, said guide rails being connected with the cover by overturning portions at their ends into contact with the edges of 105 the cover.

2. A note book comprising in combination with a cover, a C-shaped clamping spring slideable longitudinally of and embracing the cover and adapted to hold the leaves within the book, and longitudinally-extending guide rails on said cover for guiding said clamping 110

- spring, said guide rails formed with rivet-like projections adapted to be passed through the sides of the cover.
3. A note book comprising in combination with a cover, a C-shaped clamping spring 5 slideable longitudinally of and embracing the cover and adapted to hold the leaves within the book, and longitudinally-extending rails guiding said clamping spring on said cover, said guide rails formed with longitudinal grooves and said clamp formed with rounded edges engaging in said grooves.
4. A note book comprising in combination with a cover, a C-shaped clamping spring slideable longitudinally of and embracing the 15 cover and adapted to hold the leaves within the book, and longitudinally-extending guide rails for guiding said clamping spring on said cover, said clamp formed with a roughened surface, substantially as and for the 20 purpose set forth.

In testimony whereof I have signed my name to this specification.

MAX VOGEL.
